8-28

No. 13,434

Nov 14, 1882

UNITED STATES PATENT OFFICE.

JOHN L. POPE, OF CLEVELAND, OHIO.

DESIGN FOR A WRENCH.

SPECIFICATION forming part of Design No. 13,434, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for S-Wrenches, of which the following is a specification, reference being had to the accompanying engraving, forming part thereof.

My invention relates to a design for what are known as "S-wrenches;" and its novelty consists in certain features of ornamentation, as shown in the illustration forming part of this specification, and as will be hereinafter more particularly described and claimed.

The wrench shown in the accompanying engraving is not novel as far as its general configuration is concerned. It possesses the "S" form, from whence it derives its name, and is provided at either end with a jaw to adapt it to the usual purposes of turning or holding nuts or bolt-heads, as well understood. I have improved the appearance of this kind of wrench by using a bead, *a*, (formed in the casting of the article,) which extends along each edge of the wrench for the whole length thereof, and follows the various curved portions. I have further ornamented this wrench by employing ribs at the jaw ends thereof. These ribs (marked with the letters *b*) follow the three sides of the jaws, and then branch outwardly from the angles of the jaws until they meet and join the bead or molding *a*, which surrounds each edge of the wrench. While these ribs are shown as having flat faces, they may, however, be made in practice with rounded or other shaped tops or faces, and yet be not outside of my novel design. The shank or

handle of the wrench between the two beads *a a*, I have embellished by beveling the metal and forming a central peaked portion, as at *c*, ⁴⁰ which is bifurcated at both extremities and runs up to the rib branches *b*.

Some of the features of ornamentation illustrated may be used on wrenches other than the kind here shown and described, and I ⁴⁵ therefore do not consider myself as limited to the kind of wrench on which I have chosen to apply my novel design.

What I claim as of my invention, and desire to secure by Design Letters Patent, is—

1. An S-wrench provided with the bead *a*, substantially as shown and described.

2. A wrench the jaw ends of which are ornamented with ribs *b*, substantially as shown and described.

3. A wrench the jaw ends of which are ornamented with ribs *b* and branch ribs extending therefrom to the edges of the implement, substantially as shown and described.

4. A wrench - handle having the central ⁶⁰ peaked portion, *c*, substantially as shown and described.

5. A wrench having the central peaked portion, *c*, with peaked bifurcated extremities, substantially as shown and described.

6. A wrench ornamented substantially as shown and described.

In witness whereof I have hereunto set my hand this 17th day of July, 1882.

JOHN L. POPE.

In presence of—

L. S. FISH,
FRANK N. WILCOX.
